UNITED STATES PATENT OFFICE.

ORIN W. WARD, OF NEW YORK, N. Y.

BOX CONSTRUCTION.

1,088,493.

Specification of Letters Patent. Patented Feb. 24, 1914.

Application filed April 1, 1913. Serial No. 758,122.

To all whom it may concern:

Be it known that I, ORIN W. WARD, a citizen of the United States, and a resident of the city of New York, borough of Manhattan, in the county and State of New York, have invented a new and Improved Box Construction, of which the following is a full, clear, and exact description.

This invention relates to the construction of cheap strong articles of furniture such as stands, taborets or the like, and also to the construction of storing and shipping devices such as hat boxes, etc.

Among the objects of this invention is to provide means whereby devices of the above indicated characters may be quickly and accurately assembled and which present a neat and ornamental appearance, the same having also the capability of being knocked down or taken apart for purposes of storing away in small places or for shipment empty.

The foregoing and other objects of this invention will hereinafter be more fully described and claimed and illustrated in the drawings forming a part of this specification in which like characters of reference indicate corresponding parts in all the views, and in which—

Figure 1 is a perspective view of one of the many forms which this invention may assume; Fig. 2 is a perspective view of an upper corner of the box with the cover omitted; Fig. 3 is a similar view of a lower corner; Fig. 4 is a sectional view of the same showing the bottom angle strips in plan; Fig. 5 is a perspective view of an end of one of the bottom corner strips; and Fig. 6 is a transverse sectional detail on the line 6—6 of Fig. 1.

The several parts of this device may be made of any suitable materials, and the relative sizes and proportions, as well as the general design thereof, may be varied to a certain extent without departing from the spirit of the invention hereinafter specifically claimed.

In the making of these boxes I prefer four kinds or types of material or stock, the same including three forms of strips preferably of wood, and each form including one or more kerfs for the reception of the four characters of stock, namely, plates or boards of any suitable material, such as wood, paper or other artificial composition.

The strips 10 adapted for the upright cor-

ners and the horizontal bottom angles each consist of a structure having an outside angle 11 of any suitable form depending upon the general form of the finished article, 60 but herein illustrated as being at 90 degrees, and thereby forming two sides kerfed as shown at 12. These kerfs are of uniform depth and space from the outside of the strip. They also are of uniform width corresponding to and for the reception of plates 13 of any suitable cheap and substantially stiff material. The corner upright strips *a* are sawed, according to the general form of the box, with upper and lower parallel ends 70 *a'* and *a''*. The base corner strips *b* of the same material as the strips *a* are formed, as shown in Fig. 5, with tongues 14 projecting into the ends *a''* of the corner pieces. Each strip *b* also is provided with a vertical face 75 15 adjacent the tongue 14 which matches the adjacent vertical edge 16 of the strip *a*. Leading outward from the face 15 is a mitered plane face 17, and extending at a right angle therefrom is another mitered 80 face 18. The faces 18 of adjacent ends of the bottom strips *b* coöperate with each other as shown in Fig. 4, and the faces 17 of adjacent strips lie in the same plane and against the diagonal face 19 of the corner piece *a*. The strips 10 from which the corner pieces *a* and *b* are formed are of maximum strength because of the form shown, and by mitering the ends, as illustrated in Figs. 85 4 and 5, of the strips *b*, they are fitted 90 snugly to the lower ends of the strips *a* and fitted to each other in a neat and strong manner.

The edge strips *c* are of flat construction having a single kerf 12. The thickness of 95 these strips is the same as the width of the face 16 above described, and the width of the strips *c* corresponds to the corresponding dimensions of the other parts. In order to fit the strips *c* to the tops of the corner 100 pieces *a*, each end of each of them is sawed to provide a tongue 14' corresponding to the tongues 14 previously described and extending into the kerfs 12 of the corner pieces. Bottom plates 13' and side plates 13'' are 105 cut of a form and size corresponding to the form of the structure and dimensions of the kerfs 12 of the several parts.

When the strips *a*, *b* and *c* are assembled in the manner already stated with the plates 110 13 slipped into place in their respective kerfs, any suitable means may be employed

to lock the parts together through the tongues 14 and 14'. If the structure is to be permanent, glue may be used, or if the structure is to be knocked down, friction 5 may be depended upon to hold the parts together, or any other suitable fastening means may be used.

The cover, if used, may consist of a series 10 of strips *d* of angular formation as shown in Fig. 6, and adapted to rest upon and embrace the edge strips *c* and ends *a'* of the corner pieces. These strips *d* are provided each with a single kerf 12 for the reception 15 of a cover plate 13°. In cutting the strips *d*, single simple miters are used, as shown in Fig. 1. It will be apparent, therefore, that the formation of the boxes may be carried out with rapidity and accuracy when the stock is provided as above described.

20 Having thus described my invention, I claim as new and desire to secure by Letters Patent:—

1. The herein described box construction 25 comprising corner strips, each having a pair of longitudinal kerfs and a diagonal inner face, bottom corner strips each having end tongues extending into certain of the kerfs of the first mentioned strips, the ends of said bottom corner strips also being formed 30 with faces coöperating with the diagonal faces of the corner pieces and with each other, said bottom corner strips also being provided with longitudinal kerfs, upper edge strips extending from corner to corner

and each having a kerf in the same plane as 35 the corresponding bottom strip kerf, and bottom and side filler plates located in the several kerfs aforesaid.

2. The herein described box construction comprising corner strips, each having a pair 40 of longitudinal kerfs and a diagonal inner face, bottom corner strips each having end tongues extending into certain of the kerfs of the first mentioned strips, the ends of said bottom corner strips also being formed 45 with faces coöperating with the diagonal faces of the corner pieces and with each other, said bottom corner strips also being provided with longitudinal kerfs, upper edge strips extending from corner to corner 50 and each having a kerf in the same plane as the corresponding bottom strip kerf, bottom and side filler plates located in the several kerfs aforesaid, means to secure the parts together, and a cover comprising a 55 series of angular strips adapted to rest upon and embrace the upper ends of the corner strips and the edge strips, said cover strips being mitered together at their corners, and a filler plate mounted within said cover 60 strips, substantially as set forth.

In testimony whereof I have signed my name to this specification in the presence of two subscribing witnesses.

ORIN W. WARD.
